US0D1065589S

(12) **United States Design Patent** (10) **Patent No.:** **US D1,065,589 S**
(45) **Date of Patent:** **** Mar. 4, 2025**

(54) **FLOOD CONTROL BARRIER**

(71) Applicant: **Foshan Litong Canopy Co., Ltd.**,
Foshan (CN)

(72) Inventor: **Yuxiang Ou**, Foshan (CN)

(73) Assignee: **Foshan Litong Canopy Co., Ltd.**,
Foshan (CN)

(**) Term: **15 Years**

(21) Appl. No.: **29/890,452**

(22) Filed: **Apr. 24, 2023**

(51) LOC (15) Cl. **25-02**

(52) U.S. Cl.

USPC **D25/38.1**; D10/113.3

(57) **CLAIM**

The ornamental design for a flood control barrier, as shown and described.

DESCRIPTION

FIG. 1 is a first perspective view of a flood control barrier showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG.

1.

The broken lines shown in the drawings depict portions of the flood control barrier that form no part of the claimed design.

1 Claim, 9 Drawing Sheets
